UNITED STATES PATENT OFFICE

EMIL W. RIPPE, OF OHIOWA, NEBRASKA

WIRE ROLLER

Application filed August 7, 1928. Serial No. 298,094.

This invention relates to a wire roller and has for its prime object to provide a structure which may be conveniently mounted on a wagon body, in place of the tail gate, so as to be easily transported, and which includes mechanism whereby wire may be easily collected or paid off in the tearing down or building of fences on a farm, or under any other circumstances.

10 A still further very important object of the invention resides in the provision of a wire reeling structure of this nature which insures that the wire will be wound tightly on the reel, and which also insures that the 15 wire will be taken off from the reel, so that it may be hung in the building of a fence in a taut manner.

A still further very important object of the invention resides in the provision of an 20 apparatus of this nature which is exceedingly simple in its construction, inexpensive to manufacture, strong and durable, thoroughly efficient and reliable in use and operation, and otherwise well adapted to the purpose for 25 which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a top plan view of the apparatus embodying the features of my invention.

35 Figure 2 is a detail elevation of the wire guide mechanism.

Figure 3 is a sectional view of the mechanism.

40 Figure 4 is a sectional view, taken substantially on the line 4—4 of Figure 3, and

Figure 5 is a detail view, showing one of the end cruciforms of the reel.

Referring to the drawings in detail, it will be seen that the numeral 5 denotes the wagon body, provided at its rear end with the usual cleats 6, for receiving the tail gate. A panel 7 is mounted in the cleats 6, in place of the usual tail gate, and has bearings 8 mounted thereon. A shaft 9 is journaled in the bearings, and endwise movement of the shaft is

prevented by collars 10 on said shaft. This shaft extends to one side of the wagon and has a disc 11 provided with a hub 12, journaled thereon. A reel 14 is provided with cruciform ends 15 and is fixed on the extended end portion 16 of the shaft 9 at one side of the wagon, which end 16, extends end through a hub 17 of a disc 18, which is provided with an annular peripheral flange 19, extending over the periphery of the disc 11. 55 60

A plurality of ring plates 20 are mounted on bolts 21, carried by the disc 18, and a plurality of discs 23 are alternately arranged with respect to the discs 11, 18, and plates 20, and are mounted about the end portion 16 of the shaft 9, and are fixed for rotation with the disc 11, by means of bolts 24. A spring 25 is disposed about the shaft 9, and impinges against a collar 26, placed on the shaft 9 and against the hub 12 to hold the discs 23 and the plates 20 in frictional engagement with each other and also in respect to the discs 11 and 18. A sprocket 27 is formed on the hub 12, and the chain 28 is trained thereover and trained over a sprocket 29, operatively connected with one rear wheel 30 of the wagon. 70 75

80 A bar 31 is disposed across the rear portion of the wagon and is held in place by a bolt 32, engaged in one edge thereof and having its lower end formed with hook 33 to engage under the wagon. A lever 34 is pivoted as at 35, on the other end of the bar 31 and has a bracket 36 at the lower end thereof with a resilient coil member 37, formed thereon. 85 The lever 35 is provided with a lateral extension 38, so that it may be conveniently swung. A rod 39 is engaged with the forward portion of one side of the wagon body as is indicated at 40 and is engaged with the extremity of the resilient coil member 37. The wire to be wound on the spool is first passed through the member 37 to be then wound upon the spool, and as the handle 38 is actuated to rock the lever 35, the coil member 37 acting in the nature of a guide will be moved across the front of the reel lengthwise of the reel, and thus evenly distribute the wire from the reel as it is being wound thereupon. 90 95

100 Obviously, when the wagon proceeds along,

it will cause the rotation of the reel 14 so that wire may be wound thereon, since this reel is fixed in relation to the hub by means of an extension 43 on the hub, and the bolt 44. Obviously, in this manner, wire may be paid off from the reel. The frictional drive provided for the reel allows the reel to slip if it is turned faster than necessary to properly wind or unwind the wire on the reel, in order to maintain the necessary tension incident to the winding or unwinding of the wire upon the reel.

This apparatus will prove of assistance to the farmer in many ways, since it makes it easy to take the fence away, for all that is necessary is that the farmer has to take the wires from the post, drop the lower wire, and drop the top wire on the other side of the post, then tie the wire to the reel and drive the wagon along one side and back on the other side, and the wire is on the reel. Then, when setting a fence, a farmer can tie the end of the wire to the post and it will be paid off of the reel while driving along, and setting the rest of the posts. Obviously, the structure is adaptable to many other uses, other than that given here, by way of example.

It is thought that the construction, operation, utility and advantages of the invention will now be quite apparent to those skilled in this art, without a more detailed description thereof.

The present embodiment of the invention has been disclosed in detail merely for the purpose of exemplification, since in actual practice it attains the features of advantage enumerated as desirable in the statement of the invention and the above description.

It will be apparent that changes in the details of construction, and in the combination and arrangement of parts as will be herein-after more fully described and claimed may be restorted to, without departing from the spirit or scope of the invention.

45 I claim:

In combination with a wagon body having a tail gate guide, of a panel removably fitted in said guide having horizontally aligned bearings, a shaft rotatable in the bearings 50 extending beyond one end of the wagon body, a hub rotatable on the shaft, a wire reel on the shaft, means detachably connecting the reel to the hub, a frictional drive for the hub, a horizontal support detachably secured to the body in advance of the reel, and a wire guide pivoted to said support.

In testimony whereof I affix my signature.
EMIL W. RIPPE.
